GARMENT SUSPENDER

Filed Jan. 2, 1936

James Ward Dick, Inventor

UNITED STATES PATENT OFFICE

2,105,908

GARMENT SUSPENDER

James Ward Dick, High River, Alberta, Canada

Application January 2, 1936, Serial No. 57,223
In Canada September 24, 1934

6 Claims. (Cl. 241—18)

In the specification, the term "braces" means suspenders or supports, or that device consisting of straps (of whatever material) and other accessories for supporting articles of wearing apparel on the human body.

The term "tab" means that part of the "brace" which attaches directly to the article of clothing.

My invention relates to improvements in braces in which a swivel connection is incorporated; the objects being:

First.—To provide an easy means of removing the twist out of the brace or tabs without the necessity of unfastening the tabs from either the article of clothing or the brace, and which will automatically assume a free working position without danger of injury and will not accidentally come apart.

Second.—To enable the brace or tabs to be attached to the article of clothing at random, the connection taking care of any accidental twist in either the brace or tabs.

Third.—To provide a simple arrangement for the disconnection of the brace straps from the tabs, thereby saving the trouble of unfastening the tabs from the wearing apparel.

Fourth.—To fill a long-felt want; and to enable the wearer of the brace to adjust the same, and more especially the rear part, while in use, with self-help only; and to provide a degree of comfort and convenience not hitherto attainable.

I attain these objects by incorporating at any suitable position or positions in the design of the brace, but preferably at the junction of the tabs with the brace straps, a swivelling device, being a fastening so constructed as to allow the parts fastened to rotate about the axis of their fastening and in which the portion to be attached to the garment maintains a position normal to the main supporting member.

Fig. 1 is a front elevation showing my improved form of swivel garment suspender.

Fig. 2 is an elevation in section through line BB, Fig. 1.

Fig. 3 is an inverted plan view of Fig. 1 in section through line CC and shows the underside of member 19.

Fig. 4 is a cross section at DD (Fig. 1) showing opening 15 connecting with the slot 16.

The accompanying drawing illustrates a practical application of my invention, in which the looped shaped member 19 is supported in the looped end of the strap 13 of the suspender.

The member 19 has the lower portion 19' there-
55 of formed centrally between its ends, with a boss

19x which is provided with a pivot hole 17 and a slot 16 extends laterally from said pivot hole dividing one-half of the portions 19' of the loop member from the said pivot hole to the opening 15 at one end of the loop thus forming paired 5 resilient guides.

The garment fastening tabs 20 are connected to a loop member 11 the upper portion 11' of which is formed with a central boss 11x which is provided with a hole 17' in which a pin 12 10 is secured. The stem of the pin 12 is formed with a head 12' spaced from the upper member of the loop 11 and this head is adapted to enter the opening 15 at the outer end of the slot 16 in the loop member 19, said head engaging the 15 upper surfaces of the divided portion 19', while the stem of the pin slips freely into the slot.

The inner and opposite walls of the slot 16 are formed with inwardly projecting detents or ridges 18, arranged closely adjacent to the pivot hole 17 and the space between said detents reduces the width of the slot so that pressure is required to spring the resilient divided portions of the member 19 apart and to force the stem of the pin therebetween in order that it may enter the 25 pivot hole.

The stem of the pin 12 is adapted to fit loosely in the pivot hole 17 so that it may swing in suspension on its head 12', but the detents 18 prevent the escape of the said pin from the pivot 30 hole into the slot 16, said detents also prevent the pivot pin being tilted to a position other than substantially normal to the member 19' accidentally or without the application of force 35 against the pin in a direction longitudinally of the slot 16. The pin is thus held from being accidentally disconnected or fouled in the slot so that it will not be broken or injured in the ordinary use of the device.

The opening 15 (Fig. 1 and Fig. 3) may be arranged at any desirable point in the member 19.

In my improvement the pivot hole member of the separable swivel connection will allow of retraction taking up the expansion required to pass the stem of the connecting member when it 45 is forced in or out of the pivot hole.

The position of the male and female parts of the connection may be reversed in the braces, if desired.

It is conceivable that one design of the fastener may be more suitable than the other at different parts of the brace and may be combined in the same pair of braces, and that the fastener may be manufactured from any suitable material.

I am aware that, prior to my invention swivel fastenings for braces to support wearing apparel have been made, I, therefore, do not claim these broadly but what I do claim as my invention and 5 desire to secure by Letters Patent is:—

1. Braces or suspenders comprising shoulder straps, tabs for attachment to a garment and a separable swivel connection between said straps and said tabs pivoting about a vertical axis and 10 having a slot in one member extending from a pivot hole along its base to one side and widened at the top to disengage the pivot pin and having projections or ridges formed on the inner end of the slot.
- 15 2. Braces or suspenders comprising shoulder straps, tabs for attachment to a garment and a separable swivel connection between said straps and said tabs pivoting about a vertical axis and having a slot in one member extending from the pivot hole along its base to one side and widened at the top to disengaging the pivot pin and means for automatically preventing the accidental uncoupling of the swivel connection.
- 20 3. In a garment suspender, a member having a stem provided with a head, a member adapted to engage said head having a pivot hole to loosely receive said stem and also having a slot to permit the entry of the head and the passage of said stem to said pivot hole, the sides of said slot being relatively movable toward and away from each other and adapted to hold said stem from accidental displacement from the pivot hole.
- 25 4. In a garment suspender, a member having a stem provided with a head, a member adapted to engage said head having a pivot hole to loosely

receive said stem and also having a slot extending to said pivot hole, said slot having resilient side walls converging adjacent to the pivot hole and adapted to spread to permit the passage of said pin to the pivot hole and said side walls also having portions to retain the pin in a position substantially normal to the member in which the pivot hole is arranged. 5

5. In a garment suspender, a member having a stem provided with a head, a member adapted to engage said head in a swivel support having a slot to permit the entry or removal of said head and stem, the walls of said slot being adapted to be spread apart to permit the entry of said stem to its normal operative position, and to automatically return to their normal position following the entry of the stem, and hold said stem in its operative position normal to the slotted member against accidental displacement. 10

6. In a garment suspender, a member having a stem provided with a head, a member adapted to engage said head in a swivel support with its stem extending through a centrally arranged pivot hole, the latter member having a slot leading to said pivot hole, said slot being enlarged at its outer end to permit the entry of the head and stem and constricted at its inner end adjacent to the pivot hole to prevent free entry and exit of the stem to the pivot hole, the walls of said 25 slot being resilient and permitting the forcing of the stem to and from the pivot hole and adapted to retain the stem in said hole against accidental displacement. 30
